INVENTOR
HARRY F. LEWIS

BY
Ernest H. Johnson
HIS ATTORNEY

UNITED STATES PATENT OFFICE.

HARRY F. LEWIS, OF HAMDEN, CONNECTICUT, ASSIGNOR TO THE L. CANDEE & COMPANY, OF NEW HAVEN, CONNECTICUT, A CORPORATION OF CONNECTICUT.

CEMENTING MACHINE.

Application filed April 8, 1925. Serial No. 21,565.

This invention relates to a cementing machine, more particularly to a machine for cementing the edge portions of sheet material, such as the bottoms of shoe uppers.

In the making of composite rubber and fabric footwear having fabric uppers it is necessary to cement the bottom edge of the upper where it is turned over and secured to the insole. Prior to my invention this operation has been performed manually. As an example of the manner in which this operation is performed, in cementing the uppers of arctics or gaiters the operator disposes a number of uppers in superposed relation with the lower edges successively projecting in a shingled arrangement, the projecting portion of each upper being of a width equal to that which is to be cemented. While holding the uppers down the operator applies the cement over all the exposed edges in a single operation with a spreading tool or brush. While it would appear that this operation could be performed rather rapidly considerable expenditure of time and labor is required, as to secure a good union the cement should be driven into the interstices of the fabric to some extent and to properly do this requires some time. Even then it is impossible to get the desired amount of cement on the uppers in a single operation, and a second application of cement is necessary after the first has dried.

An object of my invention is to provide a simple, cheap and rapid machine for cementing sheet material, such as the lower edges of shoe uppers. Another object is to provide a machine for frictionally applying the cement in order to secure proper penetration. Another object is to provide a machine capable of applying the requisite amount of cement in a single operation.

Other objects will appear in the detailed disclosure in the specification and claims.

Without intention to limit the invention otherwise than as required by the prior art, the same consists broadly in providing a rotary device cooperating with a table or support to feed the work, which device also cooperates with a rotary cementing device rotating in opposite direction and at a higher speed to frictionally apply a coating of cement of the desired extent.

For a detailed disclosure of the invention

reference is had to the accompanying specification and drawings, in which latter,

Fig. 1 is a front elevation of the machine;

Fig. 2 is a side elevation thereof;

Fig. 3 is an enlarged detail perspective of the cementing mechanism; and

Fig. 4 is a sectional detail of the cementing mechanism and cement supply means.

Referring to the drawings the numeral 1 designates a base on which is mounted the main frame 2 of the machine. Disposed adjacent the frame is a column 3 on which is mounted an electric motor 4, the drive shaft of which carries a pulley 5 which through the belt 6 drives a pulley 7 secured on the main shaft 8 of the machine, which latter shaft is journalled in the frame 2 and column 3. In order to provide for adjustments of the belt 6 the base 9 of the motor is mounted on a pivot 10 at one end, and by means of an adjusting screw 11 the opposite end of the base may be raised to thereby tighten the belt as shown in Figure 1. A switch 12 mounted on the column 3 controls the motor. It is obvious, however, that any other suitable form of drive for the machine may be employed.

The shaft 8 extends through to the front of the frame 2 and has secured thereon a cementing roll or wheel 13, a portion of the periphery of which is enlarged and knurled as shown at 14. A cement receptacle or trough 15 encloses the lower portion of the cementing wheel 13 and is detachably secured to the frame 2 by means of the pivot bolts 16 and wing nuts 17. A cement tank 18 is disposed in inverted position on the frame 2 and has fixedly secured to its neck a flanged outlet ring 19, which ring is removably secured to the frame 2 of the machine by pivot bolts 20 and wing nuts 21 (Figs. 1 and 2). The flow of cement from the tank 18 is controlled by a flap valve 22 operated by the lever 23, and the cement issuing from the tank flows down an inclined channel 24 in the frame to the trough 15.

A work table 25 is secured to a bracket 25^a mounted on the frame, which table is provided with an opening 26 through which the upper periphery of the knurled portion 14 of the cementing wheel slightly projects. This table is relatively small, and where a

larger support for the article is desired a larger table 27 is provided (see Figure 3) which may be attached by means of the screw 28, this latter table having its edge abutting the edge of table 25. The bracket 25^a is transversely slotted at 29 and slideable in this slot and on the table 25 is a work guide 30, the forward end 31 of which is upwardly inclined and is also transversely inclined with respect to the length of the guide (see more particularly Figures 1 and 3). The guide is provided with a slot 32 through which projects a screw 33 for holding the guide in adjusted position.

An overhanging arm 34 is pivotally connected to the frame 2 at 35, and journalled in the arm is a shaft 36, on the rear end of which is disposed a gear 37 which is driven through an intermediate gear 38 from a gear 39 on the main shaft 8. At the opposite end of shaft 36 is mounted a work feed roll or wheel designated generally by the numeral 40. This wheel has an enlarged knurled portion 41 which cooperates with the work table 25 immediately adjacent the upper projecting peripheral portion 14 of the cementing wheel to feed the work, and the feed wheel 40 is also provided with a reduced portion 42 which cooperates with the cementing wheel in the cementing operation. The gearing is such that the cementing wheel is driven in a direction opposite to that of the feed wheel and at a peripheral speed about two and one-half times greater. Attached to the pivoted overhanging arm 34 is a pull rod 43 which can be operated by means of a foot treadle or other device, not shown, to urge the feed wheel 40 downwardly into cooperative relation with the table 25 and cementing wheel 13. A coil spring 44 is disposed around the pull rod 43 and bears against the frame 2 and a collar 45 secured on the rod, to thereby resiliently urge the arm 34 and feed wheel 40 upwardly to an operative position. Secured in the frame 2 beneath the arm 34 is an adjustable stop screw 46 (Figure 3) which limits the downward movement of the arm 34 and feed wheel 40, and by adjustment of the screw proper spacing of the feed wheel and the table and cementing wheel may be secured for different thicknesses of material.

In operation, cement is supplied to the trough 15, and the guide 25 and stop screw 46 are properly adjusted for the article to be cemented. The operator then feeds the edge of the upper or other article beneath the inclined portion 31 of the guide and between the feed and cementing wheels. Due to the cooperation of the knurled portion 41 of the feed wheel and the table 25 the work is fed along at the desired speed, and at the same time the knurled portion 14 of the cementing wheel which is rotating in an opposite direction beneath the material cooperates with the

reduced portion 42 of the feed wheel to frictionally apply a coat of cement to the edge of the upper. By reason of this opposite movement of the two wheels the cement is thoroughly frictioned or rubbed in and at the same time sufficient cement is applied in a single operation. On account of the speed of the machine and the efficient manner in which the cement is applied the operation can be performed much more rapidly and more perfectly than by hand. By reason of the detachable connection of the cement trough 15 it can be easily removed for cleaning or for attention to the cementing wheel. It will be seen from the above that a simple, rapid, easily cleaned and efficient machine has been provided for performing the cementing operation and that a very thoroughly cemented article is secured. While a specific embodiment has been shown and described it is obvious that with the detailed disclosure numerous modifications will suggest themselves to those skilled in the art, and it will also be obvious that the machine is not limited in its application to the particular operation described, since it may be used for coating with other materials than rubber cement and in connection with many other articles than shoe uppers.

Therefore it is not desired that the invention be limited otherwise than as set forth in the appended claims.

Having thus described my invention what I claim and desire to protect by Letters Patent is:—

1. A cementing machine comprising a work cementing wheel, cement supplying means therefor, a work table, and an opposed work feed wheel directly cooperating with said first wheel and table and having its periphery rotating at a lower peripheral speed in an opposite direction to the adjacent periphery of said first wheel. 105

2. A cementing machine comprising a work table, a cementing wheel projecting thereabove, and an opposed differentially driven work feed wheel cooperating with said cementing wheel and with the table adjacent the latter, the adjoining surfaces of the work feed wheel and the cementing wheel rotating in opposite directions. 110

3. A cementing machine comprising a work table, a cementing wheel projecting thereabove, and a differentially and oppositely driven work feed wheel having portions of different diameters cooperating respectively with said cementing wheel and the table adjacent the latter. 120

4. A cementing machine comprising a work table, a cementing wheel projecting thereabove, a differentially and oppositely driven work feed wheel having portions of different diameters cooperating respectively with said cementing wheel and the table adjacent the latter, and means for moving the 125

work feed wheel to and from operative position.

5. A cementing machine comprising a work table having an opening therein, a cementing wheel disposed in said opening, means for supplying cement to said wheel, and a work feed wheel cooperating with said table to feed the work in a direction opposite to the peripheral movement of the cementing wheel.

6. A cementing machine comprising a work table having an opening therein, a cementing wheel having a knurled portion projecting through said opening, cement feeding means, and a work feeding wheel having a knurled portion cooperating with said table adjacent the cementing wheel to feed the work.

7. A cementing machine comprising a cementing wheel, a work table adjacent the same, a work feed wheel relatively bodily movable with respect to the table, and means for bringing said feed wheel into cooperative work driving relation with the table adjacent the cementing wheel.

8. A cementing machine comprising a cementing wheel, a work table adjacent the same, a pivotally supported work feed wheel, resilient means urging the feed wheel away from the table, manually operable means for bringing the feed wheel and table into cooperative spaced driving relation at one side of the cementing wheel, and stop means for positively limiting the operative spacing of the table and work feed wheel.

9. A cementing machine comprising a frame, a cementing wheel projecting laterally therefrom, a cement receptacle removably attached to the frame around said wheel, a work table surrounding the upper periphery of said wheel, and a work feed wheel cooperating with said table adjacent the cementing wheel to feed the work.

10. A cementing machine comprising a cementing wheel, means for supplying cement to the lower periphery of said wheel, a work table surrounding the upper periphery thereof, a work feed wheel cooperating with the table adjacent said cementing wheel to feed the work, and a work guide in advance of the feed wheel.

11. A cementing machine comprising a knurled cementing wheel, means for supplying cement to the lower portion thereof, a work table having an opening through which the upper portion of said wheel projects, a pivotally mounted work feed wheel having a portion cooperating with the cementing wheel and an enlarged knurled portion cooperating with the table, the periphery of said work feed wheel being differentially and oppositely driven with respect to the adjacent periphery of the cementing wheel, means urging the work feed wheel out of operative position, and manual means for moving it to operative position.

Signed at New Haven, county of New Haven, State of Connecticut, this 3rd day of April, 1925.

HARRY F. LEWIS.
